UNITED STATES PATENT OFFICE.

JESSE EDWIN HIGBY, OF WHITING, KANSAS.

TIMER.

Application filed September 6, 1919. Serial No. 322,093.

To all whom it may concern:

Be it known that I, JESSE E. HIGBY, a citizen of the United States, and a resident of Whiting, in the county of Jackson and State of 5 Kansas, have invented a new and useful Improvement in a Timer, of which the following is a full, clear, and exact description.

My invention relates to timers for internal combustion engines, and it consists in 10 combinations, constructions and arrangements herein described and claimed.

An object of my invention is to provide 15 a timer which may be used for engines, such as that on the Ford automobile, but which is provided with means for protecting the timer wires, so that there is no danger of causing a short circuit.

A further object of my invention is to 20 provide a timer having a rolling contact member which is arranged to engage stationary contacts located in a vertical plane, thus facilitating the removal of dirt and grease, which will work off the contacts during the operation of the device.

25 A further object of my invention is to provide a timer which is simple in construction, has few parts, and is not liable to easily get out of order.

Other objects and advantages will appear 30 in the following specification, and the novel features of the invention will be particularly pointed out in the appended claim.

My invention is as illustrated in the accompanying drawings, forming part of this 35 application, in which

Figure 1 is a vertical section through the timer, certain parts being shown in elevation,

Figure 2 is a section along the line 2—2, 40 looking in the direction of the arrows,

Figure 3 is a section along the line 3—3, looking in the direction of the arrows, and

Figure 4 is a fragmentary section along the line 4—4 of Figure 3.

45 In carrying out my invention, I provide a contact roller 1 which is a section of a cone. This roller is preferably made of hard steel and is provided with a lug or arm 2 which fits in between outwardly turned ends 3 of 50 a clamping sleeve 4, arranged to surround a cam shaft 5.

The sleeve 4 is held rigidly to the shaft 5 by means of a pin 5^x which passes through the cam shaft 5 and which is arranged to 55 enter a notch 4^x in the sleeve 4. A cup washer 18 is held by a nut 19 over the pin

so as to prevent the latter from coming out. The arm 2 of the roller is pivotally held between the ends of the clamping sleeve 4 by means of a shouldered pin 6. A spring 7 has one end fastened to the pin 6 and the other end bears on the arm 2, tending to swing the roller about the pin 6 as a pivot.

A metal shell 8 of the shape shown in the drawings is provided, which fits in a circular recess in the engine casing 9 (see Figure 1). This shell bears a fiber disk 10 which has metal inserts 11 to form stationary contacts. These contacts are spaced so as to be engaged by the roller 1 in the manner shown in Figure 1. The fiber disk 10 on that side facing the shell 8 is provided with a peripheral channel or groove 12 in which timer wires 13 are disposed. The contact members 11 are preferably held in position by means of screws 14 which serve as binding posts for the wires 13. Screws, such as that shown at 15 in Figure 1, are provided for holding the fiber disk to the shell. The shell is provided with an eye 16, by means of which the shell may be rotated about the central axis of the cam shaft. The shell has a central recess 17 which is designed to receive the lug on the spring (not shown) which is ordinarily used in holding the so-called commutator cap of the Ford car.

The wires 13 pass out of the shell and thence to the coil box (not shown).

From the foregoing description of the 90 various parts of the device, the operation thereof may be readily understood.

During the rotation of the cam shaft 5, the roller 1, which is held by the spring 7 in close contact with the fiber disk, engages 95 the stationary contacts successively. The roller 1, travelling in substantially a vertical plane, causes any dirt, grease, etc., which may have accumulated on the stationary contacts, to work off, thereby insuring a good contact 100 and obviating the frequent danger of misfiring from these causes. The wires are not in any danger of being caught by the fan blades, and furthermore, they are removed from the dust, dirt and oil, usually found around the binding posts of the ordinary commutator cap. The device is designed to be applied to the Ford automobile engine, without any substantial change in the latter.

I claim:

A timer for internal combustion engines

having a rotatable shaft, said timer comprising an oscillatory shell, an insulating disc carried by the shell, stationary contacts carried by said insulating disc, a clamping sleeve secured to said shaft and having outwardly turned ends, an arm having one end extending between the outwardly turned ends, a shouldered pivot pin for pivotally securing said arm between said outwardly

turned ends, a roller rotatably carried by 10 said arm, said roller being a section of a cone, and a spring secured at one end to said pivot pin and arranged to bear at its other end on the pivoted arm, whereby the roller is kept in close engagement with said sta- 15 tionary contacts.

JESSE EDWIN HIGBY.
